UNITED STATES PATENT OFFICE.

EDMOND A. HUSEBY, OF CHICAGO, ILLINOIS.

CONTROL-CARRYING SLIDE FOR SELF-PLAYING MUSICAL INSTRUMENTS.

Application filed May 15, 1926. Serial No. 109,293.

This invention relates to the art of self-playing musical instruments, more especially those of the pneumatically operated type, such as player pianos; and the invention has reference more particularly to an improved structure of drawer or tray carrying the various controls, such as those governing expression devices, the tempo, the motor switch, and the roll motor.

In the earlier types of player pianos the levers, push buttons and the like through which these controls are operated were commonly mounted on or in the front edge of the key-bed or in a rail attached to the latter, and were always in full sight, thus denoting that the instrument on which they appeared was a mechanical player. In later developments of the art, with a view partly to normally concealing the mechanical nature of the instrument and partly to obviate the inartistic appearance of such mechanical devices, the practice arose of mounting these controls upon a movable support that, when the controls were not in use, as during manual playing of the instrument, could be slid or folded beneath the keybed entirely out of sight.

My present invention relates to the latter type of control supports or carriers, being more especially designed for use on self-playing grand pianos.

The general object of the invention is to provide a very simple and compact tray or drawer that may conveniently be slidably mounted on the under side of the key-bed, and shall be adapted to form a carrier or support for all of the various controls used in a pneumatic player, with the manually operated control buttons, levers and the like so disposed that the device may be brought into operative position by withdrawing only the front edge portion thereof carrying the manually operated control devices from beneath the key-bed. Other more specific objects are, to provide a convenient and compact arrangement of the various controls on the slide, to provide an improved motor switch thereon with manually operable switch-closing and opening means and an automatic pneumatically operated switch-opening device, to provide an improved control for the roll motor transmission with means, of which the current cut-off pneumatic may form an element, for actuating the same to throw the transmission in from the switch-closing means so that the elec-

tric motor operating the pumps may be energized and the pneumatic roll motor simultaneously thrown into gear with the rolls through the operation of a single push button, to provide a simple and improved push button-operated vent for the various expression controls, to provide an improved mounting and scale for the tempo lever, and to provide an improved structure and mounting of tray or drawer.

Still other objects and attendant advantages of the invention will be apparent to persons skilled in the art as the same becomes better understood by reference to the following detailed description, taken in connection with the accompanying drawings in which I have illustrated a practical and preferred embodiment of the principle of the invention, and wherein—

Fig. 1 is a top plan view of my improved control-carrying tray, and of the bearing blocks in which it is slidably mounted on the under side of the key-bed;

Fig. 2 is a vertical section through the piano key-bed showing my improved tray mounted therebeneath, the forward or withdrawn position thereof being indicated by dotted lines;

Fig. 3 is an enlarged vertical section on the line 3—3 of Fig. 1 through the push button-operated vent of one of the expression controls; and

Fig. 4 is an enlarged vertical sectional view on the line 4—4 of Fig. 1 through the current shut-off pneumatic and the vent valve controlling the roll motor transmission.

Referring to the drawings, the supporting body of the tray comprises a flat rectangular plate 10, relatively narrow front and rear strips 11 and 12 attached to and overlying the front and rear edge portions respectively of the plate 10, and a pair of slide rods 13 at their forward ends fitted into holes in the front strip 11 and in rear thereof fitted to grooves in the ends of the rear strip 12, to which they are attached by screws 14. The rods 13 are slidably supported in front and rear bearing blocks 15 and 16 respectively attached, as shown in Fig. 2, to the under side of the key-bed 17. Loose on the rods 13 are felt washers 18 designed to cushion the contact of the rear frame bar 12 with the bearing blocks 15 when the slide is fully withdrawn.

Referring now to the various control de-

5 vices carried by the slide, 20 designates the switch controlling the circuit of the pump motor. The structural details of this switch, being old and known, are not herein illustrated, beyond the switch-actuating rod 21, the inward movement of which closes the switch and yieldably locks it in closed position against the opening thrust of a compression spring 22 encircling the rod 21 and 10 abutting at one end against a fixed bracket plate 23 mounted on the plate 10 and at its other end against a collar 24 fast on the rod 21. This rod 21 extends through a hole in the front bar 11 and terminates in a projecting push button 25, appropriately marked "On". The switch is manually opened by a slide rod 26 likewise mounted in a hole extending through the front bar 11 and coupled to the switch-closing bar 21 15 20 by a lever 27; the push bar 26 likewise carrying a push button 27 appropriately marked "Off".

25 Mounted on and attached to the bottom plate 10 and lying generally lengthwise of the latter is a pneumatic 28 through which automatic opening of the electric motor switch 20, and consequent shutting off of the power, is effected, usually automatically from an aperture in the music sheet. 30 The movable leaf 28' of the pneumatic 28 is connected through an L-shaped thrust rod 29 to the push-rod 21 through which the switch is manually closed, whereby, when the pneumatic 28 is collapsed, the push-rod 35 21 is thrust rearwardly and the switch circuit is opened.

40 When the circuit through the pump motor is closed by closing of the switch 20, the normally disconnected roll motor transmission is simultaneously thrown into gear through a vent valve operated by the movable limb 28' of the pneumatic 28. This is best illustrated in Fig. 4, wherein 30 designates a tube leading to a primary valve in 45 the pneumatic action of the instrument through which, on the admission of atmospheric pressure thereto, a pneumatic is energized to throw in the transmission of the roll-driving mechanism. The tube 30 is 50 fitted onto a nipple 31 mounted in and cross-wise of the rear frame bar 12, said nipple containing a normally spring-closed air valve 32 having a projecting stem 33 by which it may be opened; the valve structure being 55 identical with that of the well-known automobile tire valve. The valve stem 33 lies opposite the movable side 28' of the pneumatic 28, the outer face of said movable side being preferably supplied with a striking plate 34. When the switch 20 of the 60 pump motor is closed by pressing the button 25 all the way in, the pneumatic is expanded through the connecting member 29, and the plate 34 strikes the valve stem 33 and opens the valve, admitting atmos-

pheric pressure, and the pneumatic which throws in the roll motor transmission is thereby energized, so that the roll motor is coupled to its work simultaneously with the energizing of the pump motor. The function of the spring 22 is to partially retract the switch push rod 21 sufficiently to withdraw the movable side 28' of the pneumatic 28 from the stem of the air valve 32 and permit said valve to close, without opening 75 the switch.

70 The playing and reroll movements of the music sheet are controlled through an oscillating valve 35 of known construction that is mounted on the bottom plate 10 and is formed with a group of nipples connected to corresponding air conduit tubes 36, 37, 38, 39 and 40 that extend along on the bottom plate 10 to connection with the nipples 41, 42, 43, 44 and 45, respectively mounted 85 in and extending through the rear frame bar 12; said last-named nipples communicating through flexible tubing with the pneumatic devices by which the usual music roll transmission clutch is shifted to effect the 90 playing and reroll movements of the music sheet. The cap or cover constituting the distributing member of the valve 35 is formed with a radial stem 46 lying between two pins 47 and 48 on a sliding rod 49 95 mounted in a hole in the front bar 11 of the frame and equipped with a push button 50 bearing on its face the symbol "On". By pushing the button 50, the valve 35 is actuated in a direction to shift the transmission clutch to effect the winding of the music sheet on the receiving spool as the piece is being played. The valve 35 is actuated in the reverse direction to shift the transmission clutch and drive the music spool to 105 effect the rapid rerolling of the music sheet by a sliding rod 51 mounted in the front bar 11 and carrying the push button 52 appropriately marked "Off"; the rod 51 being coupled to the rod 49 by a lever 53 which 110 relatively reverses the directions of movement of the two rods when either is actuated.

115 Also mounted on the tray is a group of manual controls for the various expression devices of the instrument. These controls are all structurally identical and are, therefore, identified by identical reference numerals in the drawing. By reference to Fig. 1 it will be observed that the front bar 11 120 of the tray is somewhat widened in a forward direction at its intermediate portion, and on this widened portion is mounted a sheet-metal plate 54 provided with a group of round apertures 55 (Fig. 3). The holes 55 register with underlying holes 56 formed in and through the bar 11. Midway of the hole 56 is secured a guide block or spider 57 apertured to fit the stem 58 of a push button 59 that normally projects above the plate 125 130

54. On the lower end of the stem 58 is secured a plunger 59' equipped on its lower side with a facing 60 of soft rubber or the like that is normally pressed upwardly by a leaf spring 61 attached as by screws 62 to the rear portion of the under side of the bar 11. To the under side of the bar 11 above the spring 61 is glued a washer 62' of felt, rubber or like soft material, the central aperture of which registers with an air duct 63 formed in the bar 11, said duct communicating with a nipple 64 fitted therein and projecting sufficiently beyond the rear edge of the bar 11 to permit the telescoping attachment of a rubber tube 65, which latter extends across the tray and at its other end is telescoped over a similar nipple 66 mounted in and extending through the rear bar 12 of the tray. To the rear ends of the nipples 66 are connected flexible tubes (not shown) which extend to the several pneumatic actuating mechanisms of the expression devices of the instrument. The admission of atmospheric air to the duct 63 actuates the expression mechanism controlled by said duct; and the admission of such atmospheric pressure, when desired, is manifestly obtained by a simple depression of the push button 59 which bends the spring 30 valve 61 out of closing contact with the washer 62' and thus opens the vent duct 63. The characters of the various expression controls are shown by suitable symbols on the plate 54 associated with the several push buttons, as clearly indicated in Fig. 1. To facilitate the attachment of the spring valve 61, the forward edge portion of the bottom plate 10 is countersunk, as shown at 10' in Fig. 3.

40. The tray also carries the tempo lever. This latter, indicated by 67 in the drawings, is pivoted at 68 on the rear bar 12, and extends forwardly across the bottom plate, its forward or handle portion 67' being downwardly offset and extending through a horizontal slot 11' in the front bar 11. On said front bar above the slot 11' is attached a metal plate 69 bearing on its upper surface the usual tempo scale 70. Overlying and 50 co-operating with said scale is a pointer 71, the stem or shank portion of which is attached to the lever 67 as by screws 72. The rear arm 67a of the tempo lever lying beyond the pivot 68 is connected, by suitable flexible means permitting the limited in and out movements of the tray, with the usual throttle or choker valve of the tempo box.

60. By reference to Fig. 1 it will be observed that the distance between the washers 18 and the front bearing blocks 15 in which the tray is mounted is equal to the central or maximum width of the front bar 11 of the tray carrying the push buttons and the tempo lever handle; in consequence of which, when 65 the tray is fully withdrawn from beneath the

key-bed, only the front bar 11 and the control-operating devices mounted thereon are exposed to view. It will also be noted that the described mechanism, with the exception of the tempo lever, dispenses entirely with handle levers for actuating the various controls, substituting therefor slide rods and push buttons which are much simpler and less obtrusive in appearance and require less space for manipulation.

75. While I have herein shown and described one simple and practical embodiment of the invention well adapted to effectuate the stated purposes and objects thereof, it is manifest that numerous changes and variations in the structural details and relative arrangement of the parts may be resorted to without involving any substantial change in the structure itself or sacrificing any of the merits and advantages thereof. Hence, I do not limit the invention to the particular embodiment shown for purposes of illustration, but reserve all such variations, modifications and mechanical equivalents as fall within the spirit and purview of the claims.

80. I claim—

1. The combination with the key-bed of a mechanical playing instrument, and a tray slidably mounted beneath said bed, of an electric circuit switch mounted on said tray, 95 and means for operating said switch projecting through the front edge of said tray.

2. The combination with the key-bed of a mechanical playing instrument, and a tray slidably mounted beneath said bed, of an electric circuit switch mounted on said tray, 100 and a pair of push-rods for closing and opening said switch slidably mounted in and projecting forwardly of the front edge of said tray and coupled for simultaneous movements in opposite directions.

105. 3. The combination with the key-bed of a mechanical playing instrument, and a tray slidably mounted beneath said bed, of an electric circuit switch mounted on said tray, a manually operable member for closing said switch projecting beyond the front edge of said tray, a normally closed valve controlling mechanism for throwing in the roll motor transmission mounted on said tray, and means actuated by said manually operable member for opening said valve simultaneously with the closing of said switch.

110. 4. The combination with the key-bed of a mechanical playing instrument, and a tray slidably mounted beneath said bed, of an electric circuit switch mounted on said tray, a push-rod for closing said switch projecting beyond the front edge of said tray, an 115 automatic switch opening device comprising a pneumatic mounted on said tray having its movable side connected to said push-rod, and a normally closed valve controlling mechanism for throwing in the roll motor 120

125

130

transmission mounted on said tray opposite the movable side of said pneumatic and adapted to be struck and opened by said movable side when said push-rod is actuated to close said switch.

5. The combination with the key-bed of a mechanical playing instrument, and a tray slidably mounted beneath said bed, of an electric circuit switch mounted on said tray, a push-rod for closing said switch projecting beyond the front edge of said tray, an automatic switch opening device comprising a pneumatic mounted on said tray and a thrust connection between the movable side 10 of said pneumatic and said push-rod, a spring-closed valve controlling mechanism for throwing in the roll motor transmission mounted on said tray opposite the movable side of said pneumatic and adapted to be struck and opened by said movable side when said push-rod is moved inwardly to close said switch, and a spring acting to partially retract said push-rod sufficiently to retract said movable side from said valve and permit the latter to close without opening said switch.

6. The combination with the key-bed of a mechanical playing instrument, and a tray slidably mounted beneath said bed, of a play and re-roll valve mounted on said tray, air conduits connected to said valve, and play and re-roll push-rods for actuating said valve slidably mounted in and projecting through the front edge of said tray and coupled for simultaneous movements in opposite directions.

7. The combination with the key-bed of a mechanical playing instrument, a tray slidably mounted beneath said bed, said tray having air ducts in and opening through the

bottom thereof, and tubes communicating with said air ducts, of leaf spring valves attached to the under side of said tray normally closing said air ducts, and manually operated depressible plungers mounted in 45 said tray bearing at their lower ends of said valves.

8. The combination with the key-bed of a mechanical playing instrument, and a tray slidably mounted beneath said bed, of a tempo scale on said tray, a tempo lever pivoted on said tray formed with a handle portion projecting forwardly of the front edge of said tray, and a pointer on said lever overlying said scale.

9. The combination with the key-bed of a mechanical playing instrument, and a tray slidably mounted beneath said bed formed with a horizontal slot in its front edge portion, of a tempo scale on said tray overlying 60 said slot, a tempo lever pivoted on said tray formed with a downwardly offset handle portion extending through and beyond said slot, and a pointer on said lever overlying 65 said scale.

10. The combination with the key-bed of a mechanical playing instrument, of front and rear bearing blocks attached to the under side of said bed, a tray comprising a bottom plate, front and rear bars attached to said bottom plate, and rods attached to and crosswise of said bars and slidably in said bearing blocks, said bars and bearing blocks constituting co-operating stops to limit the in and out sliding movements of 70 said tray, and instrument controls mounted on said tray equipped with manual operating devices mounted in said front bar of the tray.

EDMOND A. HUSEBY.
